UNITED STATES PATENT OFFICE.

FRED WEIMAR, OF CHICAGO, ILLINOIS, ASSIGNOR OF TWO-THIRDS TO T. D. HEWITT, OF FREEPORT, ILLINOIS, AND S. A. FRENCH, OF CHICAGO, ILLINOIS.

CALIPERS.

SPECIFICATION forming part of Letters Patent No. 691,682, dated January 21, 1902.

Application filed May 2, 1901. Serial No. 58,436. (No model.)

To all whom it may concern:

Be it known that I, FRED WEIMAR, a citizen of the United States of America, residing at Chicago, in the county of Stephenson and State 5 of Illinois, have invented certain new and useful Improvements in Calipers, of which the following is a specification.

My invention relates to certain improvements in calipers, designed to render more 10 easy and certain the use of the same, so that a novice may be able to obtain as accurate or even more accurate results than are possible after years of practice with the common form of caliper. The difficulty which it is designed 15 to overcome is due to the elasticity of the arms of the ordinary calipers, by reason of which accurate measurements, either with inside or outside calipers, are exceedingly difficult.

It is the purpose of my invention to provide 20 a device which may be applied to one of the points of the calipers to form an extension thereof and to be movable relatively thereto, so as to move backward from the direction of engagement of the points with such ease as 25 to avoid any springing of the caliper-arms themselves. It is also my purpose to preferably construct said device so that the extent of its movement relative to the arm of which it forms the extension may be read from a 30 graduated device provided for the purpose of registering the amount of such movement.

To such end the invention consists in certain novel characteristics, which will be described in connection with the preferred construction, and the essential features of which 35 will be defined in the claims.

In the drawings, Figure 1 is a view of a pair of ordinary calipers provided with my invention in its preferred form and shown in the 40 act of gaging the diameter of a cylindrical body. Fig. 2 is a perspective of the device which is applied to one of the caliper-arms; and Fig. 3 is a section of Fig. 2, showing the method of its application thereto.

Referring to the drawings, A represents a 45 pair of ordinary calipers having the arms $a a'$, the calipers here shown being of the ordinary form known as outside calipers.

$B B'$, Fig. 2, are a pair of plates curved pref- 50 erably to accommodate them somewhat to the

shape of the caliper-point and having lateral extensions $b b'$, spaced apart by a strut b^2 , which is secured to the two plates by means of solder or otherwise or, indeed, may be made integral therewith. One of these extensions 55 is graduated, as seen at b^3 , the purpose of which will be described below. A clamping-screw C provides means for clamping the two plates tightly to the opposite sides of the caliper-point, and a second strut or bridge b^4 , Fig. 3, 60 provides a stop for the end of said point. Between the plates and immediately beyond this bridge is a pivoted lever D, having the point d extending out beyond the caliper-point and a finger d' extending upon the opposite side 65 of the pivot to the graduation b^3 . The pivot is shown at E, and the lever should work thereon with slight frictional resistance, so as to tend to always remain in any given position and yet to move therefrom with such freedom 70 as to avoid springing of the arms of the calipers.

In using the invention the finger d' is crowded back against the plate B, as seen in Fig. 1, thereby extending the point d to its greatest 75 distance in the direction of the point of the other caliper-arm, and the caliper is applied to the article to be gaged, as is seen in Fig. 1, placing the same between the caliper-arms in the ordinary manner and drawing the caliper 80 backward to pass said article between the points thereof. Care should be taken to keep the exposed caliper-point against the object to be gaged, and as the latter passes between the points the lever D will be moved upon its 85 pivot sufficiently to permit the article to pass between it and the opposite point. The graduations afford means for readily noting the amount of movement of the lever, and a similar application of the caliper to a model or 90 sample which is to be duplicated will determine with great accuracy whether the two are of exactly the same diameter.

I recognize the possibility of great variation in form without departing from the invention, 95 and I therefore do not limit myself to the specific construction herein set forth.

I claim as new and desire to secure by Letters Patent—

1. The combination, in a pair of calipers, 100

- and with one of the contact-points thereof, of an extension supported thereon freely and independently movable by the application of force, but otherwise tending to remain in position with respect thereto, said extension being provided with means for accurately determining the extent of its movement independent of the caliper-point; substantially as described.
- 10 2. The combination with a caliper-point, of an extension secured thereto, having a graduated portion, and a pivoted lever with a shorter arm projecting beyond the caliper-point and adapted to act as a continuation thereof, and a longer arm extending to said

graduation, and movable over the same to indicate the extent of independent movement of the lever, said lever moving with sufficient frictional resistance to remain in any of its positions until force is applied to move it therefrom, substantially as described. 20

In witness whereof I have hereunto set my hand, at Chicago, in the county of Cook and State of Illinois, this 13th day of April, A. D. 1901.

FRED WEIMAR.
